UNITED STATES PATENT OFFICE.

ADELBERT E. BRONSON, OF CLEVELAND, OHIO, ASSIGNOR TO THE DILL MANUFACTURING COMPANY, OF CLEVELAND, OHIO, A CORPORATION OF OHIO.

AIR GAUGE.

Application filed August 11, 1923. Serial No. 656,930.

The present invention relates to a gauge which is particularly adapted for gauging air pressure in pneumatic tires.

The object of the invention is to provide a construction which may be encompassed in small space, and which will be of such size and shape that it may be conveniently carried in the pocket of the user.

Reference should be had to the accompanying drawings forming a part of this specification, in which Fig. 1 is a top plan view with the cover and indicator chart removed. Fig. 2 is a transverse section; Fig. 3 is a partly transverse section taken at right angles to that shown in Fig. 2.

In referring to the drawings we would note that the figures show the gauge greatly enlarged for the purpose of clearness in the description. The preferred size of the gauge is much smaller than that which is shown in the drawings, it being of convenient size to be put in the pocket of the user.

Referring to the drawings, 1 indicates a casing which is provided with a bottom and side members, and is closed by a top member 2, which in the present instance is shown as threaded onto the side members of the casing 1. The top member carries a glass plate 3 which is secured to the cover member 2 in any desired manner.

Adjacent one side of the casing member 1 there is an opening in which opening there is secured a member 4 which is stationarily held in any suitable manner. This member 4 has a recess 5 in which is located a packing washer 6, the packing washer having a central opening 7.

The member 4 also has a recessed portion 8 which contains a ball member 9 that is spring pressed by means of a spring 10, so that the ball forms a valve cooperating with the packing 6.

Secured to the member 4 is a Bourdon tube 11, one end of the Bourdon tube being secured to this member 4 and the open end of the Bourdon tube is in communication with the recess 8.

The opposite end of the Bourdon tube is closed and connected with a pivoted segment gear 12, which in turn communicates with a gear 13 which is mounted to freely

rotate upon a central post 14, the central post being secured in the bottom portion of the casing 1.

The gear 13 has secured thereto in any desired manner an arm 15 which has an upstanding finger 16. This finger lies in the path of movement of a pointer member 17, which pointer member is secured to a hub 18 which is mounted to freely turn upon the post 14. The hub 18 is held in its position and prevented from upward movement by means of a cap screw 19.

The pointer member 17 has a part with an upturned flange 20 which extends through a portion of a circle, but not a complete circle, as will be clearly seen by reference to Fig. 1. Mounted adjacent to the flange 20 is a friction member 21, this friction member having a portion which normally bears against the flange 20. The friction member is engaged by means of a spring 22 which spring is fastened at one end in a post 23 attached to or formed integral with the casing. The spring is provided with a portion which is indicated at 24 which is adapted to engage with the friction member 21. The opposite end of the spring engages with the end of a threaded adjustment member 25 which is carried in a stationary post 26. By the arrangement which has just been described, the degree of tension upon the friction member 21 may be adjusted.

Surrounding the hub member 18 is a light spring 27, one end of which is fastened to the hub 18, and the other end of which is fastened to an arm 28, which arm is fastened to the member 4 by means of a screw such as shown at 29.

The operation of the device will be clearly seen to be as follows: When the gauge is introduced to a valve stem of a pneumatic tire, the ball 9 will engage with the protruding end of the stem of the valve insides, depressing the same, while the packing member 6 engages with the upper end of the valve stem proper, thus sealing it against the escape of air.

Air under the pressure of the pneumatic tire will enter the Bourdon tube 11, causing it to expand and producing a corresponding movement of the pointer member 17. This

movement being positive, will overcome any frictional bearing of the friction member 21 upon the flange 20, and the degree of movement of the pointer 17 will be in accordance with the movement of the Bourdon tube, which will in turn be in proportion to the pressure of the air which is being gauged.

When the gauge is removed from the source of pressure the Bourdon tube will return to its normal position but the friction member 21 will retain the pointer in that position to which it will have moved so that after the gauge has been operatively connected with a valve stem, it may be removed and taken to a convenient place for reading, thus obviating the necessity of reading the gauge as it is in engagement with the valve stem.

In order to release the pointer so that it may return to its zero position, there is a plunger 30 which is mounted to have a portion extend through an opening in the lower part of the casing, thus forming in effect a protruding button 31 which may be depressed by a finger of the user. This button 31 is held in place by means of a spring 32 one end of the spring being of yoke form and straddling the plunger 30, extending between two flanges 33 and 33^a on the plunger 30, while the opposite end is fastened to the bottom of the casing.

The top of the plunger has a conical end which is adapted to engage with an extension 21^a of the friction member 21, so that when the plunger 30 is depressed it will move the friction member 21 to release its contact with the flange 20, and thereupon the spring 27 will cause the pointer to return to its initial or zero position.

It will be understood that the pointer 17 cooperates with a dial which is indicated at 34, this dial being secured inside the casing 1 in any desired manner, and when calibrated with respect to the movement of the pointer 17 will indicate the pressure of the air within a pneumatic tire or other device to which the gauge is connected.

Having described my invention, I claim:—

1. An air gauge comprising a thin flat casing having an opening in the bottom wall thereof, a Bourdon tube within the casing having one end fixed and communicating with said opening, an indicator movably mounted within the casing, means connecting the free end of the Bourdon tube with the indicator for actuating the same, a spring pressed brake within the casing for holding the pointer in that position to which it is moved in the operation of the Bourdon tube, and a manually operable plunger mounted in the bottom wall of the casing and engageable with the brake to release the same.

2. An air gauge comprising a casing having an opening, a Bourdon tube within the

casing having one end fixed and communicating with said opening, an indicator movably mounted within the casing, a movable arm operatively connected to the free end of the Bourdon tube and engageable with the indicator to move the same in one direction, a spring acting on the indicator to move the same in the opposite direction, a brake in the casing for holding the pointer in that position to which it is moved in the operation of the Bourdon tube, and means for releasing said brake.

3. An air gauge comprising a casing having an opening, a Bourdon tube within the casing having one end fixed and communicating with said opening, an indicator movably mounted within the casing, a movable arm operatively connected to the free end of the Bourdon tube and engageable with the indicator to move the same in one direction, and a spring acting on the indicator to move the same in the opposite direction, and a manually releasable brake acting upon the indicator to retain the same in that position to which it is moved by the operation of the Bourdon tube.

4. An air gauge comprising a casing having an opening, a Bourdon tube within the casing and mounted at its open end so that the open end is in communication with the opening in the casing, a post stationarily mounted within the casing, a gear member mounted upon said post, gearing means operated by the free end of the Bourdon tube and co-operating with said gear, a movable pointer pivotally mounted upon the said post independently of the gear, and an arm carried by the said gear engaging with the said pointer to move the same in one direction.

5. An air gauge comprising a casing having an opening, a Bourdon tube within the casing the open end of said Bourdon tube being in communication with said opening, and a movable indicator mounted within the casing, operative connection between the free end of the Bourdon tube and said indicator to move it in one direction, resilient means normally moving the indicator in the opposite direction, a brake co-operating with said pointer to hold the pointer in that position to which it is moved by the operation of the Bourdon tube, a spring acting on the brake to press the same into engagement with the pointer, and means for shifting the brake in opposition to its spring to release the pointer.

6. An air gauge comprising a casing, an opening in said casing, a Bourdon tube within the casing which tube is mounted at the open end thereof so that the open end is in communication with the said opening in the casing, a pivoted indicator member within the casing, operative connections between the free end of the Bourdon tube and the

- pivoted indicator to move said indicator in one direction, a spring for moving the indicator in the opposite direction, a brake to hold the pivoted member in the position in which it is moved by the Bourdon tube, a spring acting on the brake to hold the same in engaging position, means for adjusting the tension of the spring and means for releasing said brake.
7. An air gauge comprising a casing, an opening in said casing, a Bourdon tube having an open end within the casing said Bourdon tube being fastened at the open end so that the open end is in communication with the said opening in the casing, a post within the casing, an indicator member pivotally mounted upon said post, operative connections between the free end of the Bourdon tube and the indicator to move the same in one direction, a spring for moving the indicator in the opposite direction, a pivoted brake member associated with the pivoted indicator, a spring acting on the brake to hold the same in engaging position for holding the indicator in the position to which it is moved by the Bourdon tube, and a manually operable plunger for releasing the brake member.
8. An air gauge comprising a casing having an opening, a Bourdon tube having an open end which end is mounted within the casing and in communication with the opening in the casing, a post mounted in the casing, a pivoted indicator member mounted upon said post, an arm adapted to engage said pointer and move it in one direction, operative connections between the said arm and the free end of the bourdon tube, a spring engaging said indicator and moving it in a direction opposite to that in which it is moved by the said arm, a pivoted brake member adapted to engage with a portion of the indicator and hold the indicator in that position in which it is moved by the Bourdon tube, a depressible plunger mounted in the casing and adapted to engage with the said brake member to move it to releasing position.

In testimony whereof, I hereunto affix my signature.

ADELBERT E. BRONSON.
